(57) **CLAIM**

The ornamental design for a guard, as shown and described.

DESCRIPTION

FIG. 1 is a front isometric view of a guard;

FIG. 2 is a front view of the guard of FIG. 1;

FIG. 3 is a rear view of the guard of FIG. 1;

FIG. 4 is a left side view of the guard of FIG. 1;

FIG. 5 is a right side view of the guard of FIG. 1;

FIG. 6 is a top view of the guard of FIG. 1;

FIG. 7 is a bottom view of the guard of FIG. 1;

FIG. 8 is a front perspective view of a second embodiment of the guard;

FIG. 9 is a front view of the second embodiment of the guard of FIG. 8;

FIG. 10 is a rear view of the second embodiment of the guard of FIG. 8;

FIG. 11 is a left side view of the second embodiment of the guard of FIG. 8;

FIG. 12 is a right side view of the second embodiment of the guard of FIG. 8;

FIG. 13 is a top view of the second embodiment of the guard of FIG. 8; and,

FIG. 14 is a bottom view of the second embodiment of the guard of FIG. 8.

The broken lines showing environmental structure are for illustrative purposes only and form no part of the claimed design.

1 Claim, 14 Drawing Sheets
